UNITED STATES PATENT OFFICE

2,522,315

AUTOMATIC UNDERCUTTING AND GROOVING TOOL

Aaron A. Staat, Covington, Ky.

Application July 7, 1947, Serial No. 759,350

2 Claims. (Cl. 82—20)

1

This invention relates to an automatic undercutting and grooving tool.

It is an object of the present invention to provide a grooving tool adapted to be attached to the head of a lathe or screw machine which upon making abutment with the end of the work being grooved or undercut automatically causes the inward movement of the cutters for effecting the operation and whereupon at the end of the work operation an outward movement of the work will release the cutters and cause their return to their open positions.

Other objects of the present invention are to provide an automatic undercutting and grooving tool which is of simple construction, inexpensive to manufacture and efficient in operation.

For other objects and for a better understanding of the invention, reference may be had to the following detailed description taken in connection with the accompanying drawing, in which

Fig. 1 is a side elevational view of the tool with the cutters about to be extended upon the work to effect the cutting operation.

Fig. 2 is an end elevational view of the tool.

Fig. 3 is a longitudinal cross-sectional view of the tool taken generally on line 3—3 of Fig. 2.

Fig. 4 is a fragmentary and cross-sectional view taken in another plane and on line 4—4 of Fig. 2.

Fig. 5 is a transverse cross-sectional view taken on line 5—5 of Fig. 1.

Fig. 6 is a longitudinal cross-sectional view taken through the operating mechanism for the cutters.

Fig. 7 is a transverse cross-sectional view taken through the operating mechanism and on line 7—7 of Fig. 1.

Referring now to the figures, 15 represents a spindle adapted to be inserted in a chuck of a lathe or screw machine. This spindle has a projection 16 of less diameter and providing for a shoulder 17. Within the projection 16 is a central opening 18 in which there is extended a projection 19 of a plug 20 having a tapered surface 21 thereon. Ahead of the tapered surface 21 is a cylindrical projection 22 extended into a thrust plate 23 engaging with a thrust bearing 24. Surrounding the projection 16 and the plug 20 is a casting serving as a holder for the two elements. This casting is indicated generally at 26. The casting has sliding engagement with the projection 16. Within the projection 16 are grooves 27 in which can be slid elements 28 connected by a screw 29 to the cast-

2

ing 26. Upon releasing the screw 29 the element 28 can be relieved and the casting 26 can be removed from the projection 16 of the spindle. Accordingly the casting 26 is axially adjustable on the projection 16. Within the casting are springs 31 abutting a collar 32 secured over the shoulder 17 of the spindle 15. These springs will urge the casting 26 forwardly as shown in Fig. 1. When the thrust plate 23 engages the end of a work piece 33, the springs 31 will be compressed and the casting will be adjusted rearwardly to the position shown in Fig. 3.

On the front face of the casting 26 are mounted radially adjustable tool holders 34 which are normally urged outwardly by springs 35. A tool element or cutting element 36 is slidable in the tool holders and is adapted to be depressed radially inwardly against the action of spring 35 by a lever 37 pivoted at 38 to the casting 26. On the opposite end of the lever 37 is an adjusting screw 39 adapted to engage outer end of an operating member 41 within radially extending openings which is moved by the inward movement of the casting and the engagement of the operating element 41 with the tapered surface 21 of the plug 20. A cylindrical shield 42 is secured to the collar 32 and extends over the exterior surface of the casting whereby to keep dirt from entering the space between the casting and the collar 32.

30 The plug 20 is retained within the projection 16 of the spindle by a set screw 43. Operating element 41 has a set collar 44 to prevent or limit the inward displacement of the operating element 41. The holders 34 are retained on the casting 26 by bolts 45, Fig. 7. The cutter 36 is retained in the holder by a guide plate 46.

In operation, the thrust plate 23 will engage the end of the work and the casting will be moved rearwardly on the projection 16. As this happens the operating elements 41 will be raised upon the tapered portion 21 of the plug and moved outwardly to engage the adjusting screws 39 on levers 37. The opposite end of the lever 37 will bear against the top of the cutter 36 and cause the inward movement of the same into the work, whereby to cut a groove 48 in the work piece. The cutters are accordingly moved inwardly automatically as the work is brought against the thrust plate 23. When the groove 48 has finally been cut, the pressure on the work piece can be released and the cutter 36 will be automatically retracted from the work piece. The casting 26 will be returned to its forward most position by the springs 31. The operating

elements 41 and the cutters 36 will be returned by the springs 35.

While various changes may be made in the detailed construction, it shall be understood that such changes shall be within the spirit and scope of the present invention as defined by the appended claims.

I claim:

1. In an automatic undercutting and grooving tool, a spindle, a casting operatively connected to said spindle and mounted for axial adjustment thereon, resilient means for urging said casting forwardly of said spindle, means connected to said spindle providing a tapered surface, there being a plurality of radially extending openings arranged in said casting, an operating element slidably arranged in each of said radially extending openings and adapted to frictionally engage said tapered surface for controlling the inward and outward movement of said operating elements, means on the casting for engaging the end of a work piece to cause the axial adjustment of said casting inwardly and thereby cause movement of said operating elements, a plurality of cutters pivotally mounted on said casting and adapted to engage said work piece, means operatively connecting said cutters to said operating elements to cause movement of said cutters as the casting is moved axially on said spindle, and an adjusting screw operatively connected to said last named means for engagement with said operating elements for regulating the cutting depth of the cutters.

2. In an automatic undercutting and grooving tool, a spindle, a casting operatively connected to

said spindle and mounted for axial adjustment thereon, resilient means embodying a plurality of coil springs for urging said casting forwardly of said spindle, means embodying a plug connected to said spindle providing a tapered surface, there being a plurality of radially extending openings arranged in said casting, an operating element slidably arranged in each of said radially extending openings and adapted to frictionally engage said tapered surface for controlling the inward and outward movement of said operating elements, means on said casting for engaging the end of a work piece to cause the axial adjustment of said casting inwardly to thereby cause movement of said operating elements, a plurality of cutters mounted on said casting and adapted to engage said work piece, means embodying levers operatively connecting said cutters to said operating elements to cause movement of said cutters as the casting is moved axially on said spindle, and an adjusting screw operatively connected to said last named means for engagement with said operating elements for regulating the cutting depth of the cutters.
